US00D630602S

(12) **United States Design Patent**
Sheppard et al.

(10) **Patent No.:** US D630,602 S
(45) **Date of Patent:** ** Jan. 11, 2011

(54) **SCREEN FOR A TELEPHONE BASE**

(75) Inventors: **Nasahn Adam Sheppard**, Mill Valley, CA (US); **Timothy Foster Wallack**, New York, NY (US); **Jason Edward Short**, San Francisco, CA (US)

(73) Assignee: **BCE Inc.**, Montreal, Quebec (CA)

(**) Term: **14 Years**

(21) Appl. No.: **29/362,045**

(22) Filed: **May 19, 2010**

Related U.S. Application Data

(62) Division of application No. 29/292,479, filed on Oct. 12, 2007, now Pat. No. Des. 619,113.

(30) **Foreign Application Priority Data**

May 16, 2007 (CA) 120749

(51) **LOC (9) Cl.** 14-03

(52) **U.S. Cl.** D14/130; D14/142

(57) **CLAIM**

The ornamental design for a screen for a telephone base, as shown and described.

DESCRIPTION

FIG. 1 is a perspective view of a screen for a telephone base showing our new design;

FIG. 2 is a front elevational view of the screen for a telephone base of FIG. 1;

FIG. 3 is a rear elevational view of the screen for a telephone base of FIG. 1;

FIG. 4 is a left side elevational view of the screen for a telephone base of FIG. 1;

FIG. 5 is a right side elevational view of the screen for a telephone base of FIG. 1;

FIG. 6 is a top plan view of the screen for a telephone base of FIG. 1; and,

FIG. 7 is a bottom view of the screen for a telephone base of FIG. 1.

The broken lines immediately adjacent the shaded surfaces represent boundaries of the claimed design. All other broken lines are directed to environment. The broken lines and unshaded regions within the broken lines form no part of the claimed design.
